SELECTING AND TYPING MEANS FOR
PRINTING TELEGRAPHSArthur Herman Adams, Yonkers, N. Y., assignor
to Western Electric Company, Incorporated,
New York, N. Y., a corporation of New York

Application February 18, 1936, Serial No. 64,467

21 Claims. (Cl. 178—28)

This invention relates to improvements in selecting and typing means for automatic typing machines, especially for that class of typing machines electrically operated at a distance and commonly called printing telegraphs and tickers, and more particularly but not exclusively for that variety called page printers as distinct from tape printers.

Modern page printing telegraphs mainly fall into two classes: (a) typebar printers, in which individual type bars like those of typewriters are caused to strike the paper. Usually this class uses an ordinary typewriter ribbon and makes carbon copies. (b) typewheel printers, in which a wheel, or segment, having raised typefaces on its surface, is selectively moved to present the desired typeface to the paper. In these the typefaces are usually directly inked and carbons are not made.

Typebar printers generically offer advantages over typewheel printers in better visibility of matter being typed, (since the typewheel usually covers several letters) and in better ability to produce manifold or carbon copy work. They require, however, moving either the paper, usually on a platen or cylinder, much as in a typewriter, which is undesirable for operating reasons, or else moving a quite large and complex basket or frame of typebars and of selecting and operating devices. In either case they require to be materially larger. They are also inherently more expensive.

Typewheel page printers, inherently smaller and less costly because having the simple typewheel in place of the many typebars and because not having so large a printing carriage to traverse, have a further cost advantage in being able to use certain simpler and cheaper selecting mechanisms.

(c) There is a third or intermediate class, as regards typing means, attempting to combine the main advantages of both classes (a) and (b). This has been tried by utilizing the typewheel as a typebar, selectively positioning it, as by rotation, and then swinging it like a typebar against the paper. There have been other and more successful attempts in which the typewheel or unitary typeface carrying member was replaced by a selectively positioned wheel or frame carrying many individually movable pieces of type, each so light as to be capable of being in a small distance sharply accelerated against the paper by a common type bar or hammer. In this class of machine it might be said that typefaces are selectively changed before a com-

mon typebar or hammer. The present invention falls in this last class as regards the typing means preferred.

One of the difficult problems in combining the ribbon printing and manifolding features of the typebar type with the compactness and simpler selection of the typewheel type is to keep low enough the mass or moment of inertia of the type member with the many individually movable types it carries. For printing on a variable thickness of papers and carbons the types may not tip or change in angle rapidly as they are advanced to the paper, else in some cases the top of the character and in other cases the foot will strike the harder and give shaded printing. For this reason the prior art type carrying members most successful for manifolding are arranged to permit the individual types to slide in guides. This requires relatively long bodies or stems on the types and a relatively large frame, making the type member heavy and hard to position quickly without excessive shocks or stresses.

Type members in disc form bearing types on the end of pivoted radial arms have been used, but the arms are necessarily very short so that this design—though lighter—is not capable of good unshaded printing on papers and manifolds variable in thickness. One feature of my invention solves this problem by the provision, in connection preferably with the lighter disc form of type carrying member, of a common type steady or guiding member having either a parallel motion or a long radius rocking motion, to which the selected type only is locked by the printing bar, whereby very short stemmed pivoted types may individually be advanced with little or no angular change. This is very important in relation to the selective type member positioning feature of my invention that will be described, because a more massive type member with the simple and stopless selective displacement means I prefer, would require more force to accelerate and would consume time in oscillation, possibly even requiring the addition of special frictions or even of stops for attaining high speeds.

One very important feature of my invention is the just mentioned selective type member positioning means, especially in relation to the positioning of a type member on a movable carriage. To grasp the advantages of my type member selective positioning means, it must be understood that in modern typewheel printers there are two main methods of selectively positioning a type

member, whether a unitary typewheel or a frame carrying individually movable types:

(1) There may be stops selectively set, for each desired position, against which an arm of the type member may be urged by a spring, a friction, or any not positive means of applying power to move the type member an indefinite distance. In this method the type member may either continue on around, if circular, after the last selected stop has been removed from its path, or may be returned to a starting point.

(2) There may selectively and additively be imparted to the type member one or more of several definite amounts of displacement from a fixed or datum position. In this method the selectively energized positioning means for the type member may supply also the motive power to move it. The motion of the type member, when using this selecting method, may be, and preferably is, in either direction, the direction depending upon whether the total or additive displacement from the datum point determined by one code is larger or smaller than that determined by the preceding code. Thus the type member may move from any position directly to any other, neither returning to the datum point nor continuing a rotation. This is an important advantage, as regards time, shock and energy in type member displacement.

30 However, the prior art means for positioning a type member on a moving carriage, even using the simple selectively additive displacement method—method 2 above—all have involved either carrying selecting means on the moving carriage or transmitting selected motion accurately to the type member on the carriage by splined shafts, shafts and gears and/or other relatively massive mechanical transmitting mechanism.

40 My invention belongs broadly in class 2 as to selective type member positioning method, but uses, as will be seen, a flexible non-stretching tape and selectively movable looping pulleys for constraining the tape to a longer or shorter path, i. e., for effectively shortening or lengthening it. My flexible tensile means for additively imparting selected amounts of displacement to any member to be positioned, unlike those of the prior art, lend themselves, with almost no added parts, to 45 positioning a member on a movable (or even on a moving) carriage just as easily as one mounted on a fixed frame. Another advantage is that the same simple tape used as a selective displacement totalizing means and as a means of transmitting 50 totalized selected displacements to the type member on the moving carriage is equally adapted to transmit a case shift displacement to the type member which preferably carries the upper and lower case characters in two distinct 55 areas. This makes the case shift consume much less power and be completed much more quickly than where the massive platen is raised or lowered, and makes the average movements of the type member materially less than where the two 60 sets of characters alternate.

A further real advantage of the preferred form of my page printer with disc shaped type member is that it practically overcomes the advantage the type bar printer has heretofore had over 65 the type wheel printer in greater visibility of matter being typed. The printing point on my preferred disc-shaped type member is so chosen below and to the left of top center that both the line and the letter last completed are always 70 legible.

One object, therefore, of this invention is to provide an exceptionally simple low cost page printing telegraph receiver capable of manifolding and capable of cooperation with existing line and transmission equipment.

Another object is the same as the last with the added object of providing an unusually light weight member carrying the types, and light weight moving means therefor, making high speeds readily attainable.

10 Another object is to provide a printer of the type member or carrier-of-types class in which all characters already printed are legibly visible.

One object is to provide a printing telegraph machine with the types, in a disc form of carrier, 15 oriented at such an angle and struck against the paper when at a point so much to the left and below the top center as to leave visible the line and the letter last printed.

Another object is the construction of an unusually simple and low cost means selectively to position a type member or other recording member in a telegraph receiver.

Another object is the provision in a telegraph printer of one very light flexible filamentary 25 member as a common means to totalize selected elements of displacement from a datum and as a means to transmit to a type member such totalized displacement.

Another object is the provision of a page printer 30 in which one light filamentary member serves to totalize selected elements of displacement and to transmit the totalized displacement to a type member on a moving carriage.

Another object is the same as the last with the same filamentary member also serving to transmit to the type member a case shift displacement.

Another object is the provision of a light and simple selective moving means for a type carrying member or wheel which will urge the latter from 40 one selected position to the next, in either direction.

Another object is the provision of such a selective type member positioning means comprising several independently and selectively operable movers, these movers additively imparting to the type member each its own predetermined amount of displacement from a datum point.

Another object is the provision in a manifolding printer of an exceptionally light and compact wheel or disc of types, each type being individually movable to printing position on a radius exceeding the radius of the disc in order to avoid top or bottom shading with variable manifolds.

Another object is the provision of unusually 55 simple, cheap and light means for the selective rotation of a type-wheel on a moving carriage by selectively operable movers not on the carriage.

Another object is the provision of a carrier of types capable of manifold work yet sufficiently light to be positioned without long oscillation by light spring actuated tensile means, and without stops.

Another object is the provision of a ribbon 65 printing manifolding page printing telegraph receiver having an exceptionally small traveling carriage and a fixed axis paper roller whereby the overall width is reduced and paper handling and paper "tracking" adjustments are simplified.

Another object is the provision of a page printer 70 yielding regularly spaced typing by accurately registering the selectively positioned type carrier just before striking each type.

Another object is to provide a shockless stopping against one spring force of a light weight type carrier moved by an opposing spring force.

Another object is the provision cheaply of a time overlap in a printer—permitting occasional codes to be sent on time centers less than the mechanical cycle time of the printer—by means of code storage magnets capable of holding their armatures by residual magnetism until knocked down.

Another object is to construct a moving or page printing typewheel carriage for ribbon printing that is entirely devoid of selecting means.

Another object is to provide a typewheel in which the letters or so-called "lower case" type are in one contiguous group and the figures and so-called "upper case" type are in another contiguous group and to provide as a case shift a mere turn of the typewheel from one group to the other to the end of approximately halving average typewheel travel over that arrangement where upper and lower case type alternate, and to the end of making unnecessary the raising and lowering either of the typewheel or of the paper.

Other objects and advantages attained will be evident from the description.

For purposes of illustration I have shown and described a structure in accordance with my invention that is adapted primarily for cooperation as a receiving printer with any of the modern commercial keyboard or tape transmitters and line arrangements, details being shown particularly adapted for "start-stop" circuits using a Baudot type code of five time units and electrical distributors. Printing telegraphs in accordance with my invention may equally well be adapted by one skilled in the art for use on multiplex circuits, or with any well-known mechanical distributor, or with codes of more or fewer time units, or on entirely different kinds of codes.

In the drawings Fig. 1 is a sectional elevation, on line V—V of Fig. 2, being a view, from the rear of the machine, of the main typewheel selective positioning means.

Fig. 2 is a sectional elevation on line U—U of Fig. 1.

Fig. 3 is a sectional elevation of the typewheel and platen, showing typing bar and centering pin, taken along line W—W of Fig. 1.

Fig. 3A is an enlarged detail of the type hinge not clearly intelligible in Fig. 3.

Fig. 4 is a sectional elevation, like Fig. 1, looking from the rear of the machine, but on line Z—Z of Fig. 2, showing letter spacing and carriage returning mechanism not visible in Fig. 1.

Fig. 5 is an enlarged detail of the typing bar and centering pin shown in Fig. 3.

Fig. 6 is a sectional elevation on line Y—Y of Fig. 1 showing particularly the line spacing mechanism.

Fig. 7 is a sectional detail on line T—T of Fig. 1.

Figs. 8 and 9 are details of one of the five code storing magnets.

Fig. 10 is a sectional detail on line X—X of Fig. 4.

Fig. 11 is a diagrammatic view of one form of typewheel and its relation to matter being typed.

Fig. 12 is a timing diagram showing cam relations and other operating sequences.

Fig. 13 is a vertical sectional view of an alternative form of typewheel with non-rotating type guide.

Fig. 14 is a detail showing the cooperation of the type hammer and the type wheel and guide of Fig. 13.

Fig. 15 is a view from the front of the machine of the arrangement of type on the wheel of Fig. 13.

Fig. 16 is a diagram of a relation of tape and typewheel alternative to that shown in Fig. 1.

1 designates a platen or paper roller, 2 a paper guide, 3, 3 pressure rollers to cause a paper or papers to hug platen 1. These paper handling parts are not shown or described in detail, being very well-known in the typewriter and printer arts. Platen 1 and associated paper handling parts do not move axially in this machine. This is advantageous for several reasons. It is harder to cause paper to "track" properly on a moving platen, especially if fed continuously from rolls. It is less fatiguing to read messages coming in on paper that is stationary. Reciprocation of the long and massive paper and platen also takes considerable space and consumes more energy and time than the reciprocation of the light typewheel carriage to be described. 4, 4 are carriage rails extending from side to side of the machine.

5 is a carriage frame riding on rails 4, 4. This may be of metal or, in the interest of lightness, of moulder Bakelite or the like. 6 is a 25 shouldered metal stud held in boss 9 by nut 7. Stud 6 has an enlarged head 8. Typewheel body 10, preferably of moulded Bakelite or of light metal, runs on stud 6 and is confined axially between stud head 8 and washer 11 against the 30 end of boss 9. Typewheel body 10 integrally carries two circular flanges, 11 and 12, separated by a cylindrical neck portion or drum 13. A tape 14 which is preferably of very thin spring steel, but may be of woven linen rubberized, or 35 of any flexible and relatively non-extensible and non-hygroscopic construction, is attached at one end on drum 13 and wraps about it at least a full turn when not extended.

In rear flange 12 are a suitable number of accurately spaced bell-mouthed centering holes 15, one for each selectable position of the typewheel. A pointed centering pin 16 is arranged to enter holes 15 with very small clearance for accurately positioning typewheel body 10. This pin 16 is 40 moved by coupling pin 108 integral with typing hammer 28. Thus centering pin 16 is withdrawn and shot forward together with typing hammer 28. Lever 109 bearing cam roller 110 is pivoted on carriage frame 5 and is raised against spring 45 111 and hammer spring 121 by a traveling cam 112 which is journaled at 113 in web 114 of carriage frame 5. As the carriage moves, cam 112 slides axially along the central square portion of shaft 115, which is driven from the main shaft 50 55 85 by spiral gear pair 116, vertical jack shaft 117 and spiral gear pair 118. Shaft 115 also carries fixed on it cam 119 near its left end, facing the machine.

The end of lever 109 lies in a fork of the rear end of hammer 28 and there engages cross pin 120 in its slotted end, withdrawing hammer 28 from advanced position and compressing spring 121 between horseshoe collar 122 and guide lug 123 of frame 5. Horseshoe collar 122 is slipped 60 over neck 124 of hammer 28 and is kept in place by spring 121. Cushion spring 125, footing against enlarged portion 126 of hammer 28, holds collar 122 to the far end of neck 124. When roller 110 reaches the sharp drop of cam 112 spring 65 121 drives forward hammer 28, made massive by portion 126, with such energy as to compress spring 125 and strike type 21 a sharp blow with a quick but limited rebound. Thus roller 110 may stay on cam low some time, keeping pin 16 in 70 75

hole 15 without the hammer touching type 21 against the paper.

A helical torsion spring 17 surrounds boss 9 and engages a hole in frame 5 at the base of boss 9 with its one end and typewheel body 10 with its other end. A number of like holes for engaging the first end may be distributed about boss 9 in frame 5 to permit of adjusting the spring torque. Three pins 18, of which only one is fully visible in the section of Fig. 3, moulded or driven into typewheel body 10, engage radially elongated but laterally close fitting holes 19 (seen best in Fig. 1) in type guide disc 20, thus angularly locating guide disc 20 relative to typewheel body 10. 21-21 are type having stems or bodies 22. These bodies, which are preferably proportioned thin and flat end in offset or Z shaped ends 23 as shown in Fig. 3A, which are hinged or hooked in radial slots 25 in type guide disc 20. In order that disc 20 shall not be weakened by having slots 25 all in one circle, the type bodies 22 of alternate types are made slightly longer, bringing alternate slots 25 in disc 20 in different circles. The offset or Z shaped end of one of the longer bodied types is shown at 23' in Fig. 3. A relatively stiff spring 26 footing against washer 72 which is held by the enlarged head 8 of stud 6, presses guide disc 20 against flange 11, the bodies 22 of the type being interposed as shown. The outer rim of guide disc 20 is formed back to surround flange 11 as shown, and this formed back portion is slotted to receive the bodies 22 of all the types 21. It will be seen that the types are well located both radially and angularly in guide disc 20, and that they are also normally held against the back of disc 20 by the face of flange 11. But it will be seen that if disc 20 is tilted or moved away from flange 11 the types can freely swing on their hinges but only away from disc 20.

The position of hammer 28 and of the type struck by it, looking from the rear or platen side of the type wheel as in Fig. 1, is well to the right and below the top center of the typewheel, or to the left and below if looking from the front of the machine as in Fig. 11. As is seen in Fig. 11 this provides for legibility of the last letter printed. Because of this off-center printing, that type in front of hammer 28 is not visible in the strictly central section view of Fig. 3. But it will readily be understood from that view that when hammer 28—very heavy relative to guide disc 20 which may be of Duralumin or of a light embossed sheet metal construction—falls on the back of any type 21 the whole guide disc 20 is tilted about its diametrically opposite point and the type so struck is gripped firmly between the hammer pressure and the spring 26 acting through disc 20 and is swung against the paper exactly as though it were an integral part of guide disc 20.

No other type but the one struck is impelled toward the paper. In fact, due to inertia, when the Z or hinge ends 23, 23' of adjacent type are suddenly accelerated by disc 20 toward the paper, their heads momentarily react all the harder against flange 11. Hammer 28, as described, instantly rebounds, due to spring 125, from its printing position far enough to permit disc 20, under pressure of spring 26, to press all types again against flange 11. This occurs before any but the struck type can have been shaken against the paper. The long radius of action for the struck type provided by the common tilting guide disc 20 is a great advantage. It produces an

action comparable to that of type bar type in that the faces strike evenly whether on single papers or on thick manifolds.

Spring 17 urges typewheel body 10, with guide disc 20 and all the types 21, in a counterclockwise direction as viewed in Fig. 1. Tape 14, at one end wrapped on and fastened to drum 13 of body 10, passes over shift pulley 29, next over adjustable idler 30, then in order over 4-unit looper pulley 31, 1-unit looper pulley 32, 8-unit looper pulley 33, 2-unit looper pulley 34, 16-unit looper pulley 35 and fixed idler 36 to an attachment on retractor drum 37. This latter is driven clockwise, as viewed in Fig. 1, by spring 39 (Fig. 6) acting on spindle 38 on which retractor drum 37 is fastened. The rotation clockwise (in Fig. 1) of drum 37 is limited by stop pin 40, that it carries, and stop pin 41 in frame 5. Spring 39 is made approximately twice as strong in rotating typewheel body 10 (by way of tape 14) as is spring 17.

Looper pulleys 31 to 35 are journaled on studs 42-42, all alike, riveted in the ends of looper levers respectively 43 to 47. These looper levers are all pivoted on like studs, 50-50, supported between frame plates 48 and 49. They are all constructed of sheet metal, as light as possible, and at their pivoting end each is formed into a U shape to bear on studs 50 at two separated points, e. g., the U (47, 52, 51) visible in Fig. 6. This gives the steadiness of a long bearing to the looper levers with a light construction. To avoid multiplying figures, a view of the U shaped bearing end of only one looper lever, 47, has been shown. As will be seen in Figs. 1 and 6 the looper levers rock on studs 50 close to one side of frame plate 48, while the studs 42, carried at their ends, project through openings 52, 53, 54, 55 and 56 in that plate. These openings vary in height and are accurately machined on one edge.

Studs 42-42, where projecting beyond frame plate 48, carry looper pulleys 31 to 35 already mentioned. These pulleys are guided and are held on these studs, and tape 14 is kept on these pulleys by cover plate 57. This plate is removable to facilitate the threading of tape 14 and replacements in case of need. A second plate 58, of the same thickness as 57 and in the same plane, similarly confines and guards shift pulley 29 and tape 14 upon it. Cover plates 57 and 58 are attached to frame plate 48 by screws and spacing collars as best seen in Fig. 10, these screws and collars being all alike and numbered 60 and 59 respectively. To simplify the drawing, only numerals 60 are shown on Fig. 1, where the location of these screws is best seen.

Pivoted on studs 50, within the U bearings of the five looper levers 43 to 47, are respectively selectable arms 62, 61, 64, 63 and 65. These are selectively engaged with power bar 66—which is reciprocated in guides 66A by cam 74, roller 75 and spring 73—and are moved by it to the right, Fig. 1 point of view. The selective engaging means will be described later. When all or any of these five selectable arms are so moved their upward projecting lugs 67, alike and like numbered on all five arms—engage the corresponding looper levers 43-47 on their cross pieces 52. These latter show in section in Fig. 1. At the end of the travel of power bar 66 and hence of any engaged selectable arm the corresponding looper pulley will have been forced as far as it may go, thus extending tape 14 as far as that pulley may do. In this position power bar 66 dwells a brief period, holding any engaged arm, 75

looper lever and looper pulley at extreme position.

Assuming, to begin with, that retractor drum 37 has been, by spring 39, rotated clockwise to its limit where pins 40 and 41 are in contact, and that typewheel body 10 has been rotated by spring 17 counterclockwise as far as it will go, we then have the shortest possible free length of tape 14, both ends having been wound up as far as they can go. Pulley 31 is then (as shown) at the top of its path with its stud 42 in contact with the accurately located top of opening 52. Pulley 32 (as not shown) is at its low point with its stud 42 in contact on the accurate lower edge of opening 53. Pulley 33 is at its top (as not shown) with stud 42 contacting the top of opening 54. Pulley 34 (as not shown) is at its low point with stud resting on lower edge of opening 55. Pulley 35 is at top with stud 42 touching top of opening 56.

Under these conditions—shift pulley 29 remaining as shown—the length of tape 14 should be such as to bring the typewheel to rest at what may be termed the datum position. This is that position whence one angular step will bring to the typing hammer the first character of the alphabetical order used. This first letter may or may not be "A", depending upon what letter may be chosen for that code that represents one step away from datum position.

To digress, it is obvious that an order of letters on the typewheel quite different from the ABC order is the one that gives, in this mechanism, the smallest average motion of the typewheel per character typed. Letters most frequently used in juxtaposition in the language would be placed in most nearly juxtaposed relation on the typewheel; those next most frequently so used being in the next most close relation on the wheel, and those most rarely so used being the farthest apart on the wheel. There are, however, many considerations of established codes and of code interchangeability that affect the choice of alphabet order.

In the above-described shortest free length condition of tape 14, the typewheel, it was said above, should be at the datum position. If, due to a tape of incorrect length or to wear or other changes, this is not the case, an adjustment of idler pulley 30 is provided to attain this relation. When the tape is effectively too long this pulley 50 is raised, and vice versa. This is done by loosening screw 68 and turning eccentric stop 69 so as to raise or lower arm 70, then retightening. Pulley 30 rides on a stud 42 in arm 70 and is guarded and guided between frame plate 48 and cover plate 57 exactly like looper pulleys 31 to 35 except that arm 70 does not move but remains resting on eccentric 69, being always drawn down by the tension of tape 14.

This datum position or shortest free tape condition is never assumed in operation. It represents the unusable code of five "spacing" impulses. It is an arbitrary reference and adjustment point. Having established it, we may now assume that some combination of the selectable arms 61 to 65 is to be moved to the right—such as 61, 62 and 65. As will be seen from a study of the cam relations—best seen in timing diagram Fig. 12—at the time power bar 66 moves to the right, centering pin 16 is in a hole 15 and is locking the typewheel. On the assumption of a start from datum position, the typewheel will be locked there.

The motion of arms 61, 62 and 65 to the right raises looper pulley 32 and lowers looper pulleys 31 and 35. The resting or "short loop" positions

of the pulley studs 42 against the edges of openings 52 to 56 are accurately machined in relation to the extended or "long loop" positions given by bars 61 to 65. Thus looper pulley 32, on being moved away from the foot of opening 53 when arm 61 is moved to the right, takes up exactly enough tape to rotate the typewheel one angular space, i. e., the distance from one character to the next. Moving the arm 62 to the right takes up tape equivalent to four angular spaces of the typewheel; and arm 65 takes up tape equal to 16 angular spaces. Arms 63 and 64 take up 2 and 8 of these units respectively.

The typewheel being locked—in datum position by hypothesis—arms 61, 62 and 65 on operating take up amounts of tape equivalent to 1 plus 4 plus 16=21 typewheel spaces. This is at first drawn off the retractor drum 37 against the tension of spring 39. The timing is such that, when about half of the 21 units has drawn off drum 37, centering pin 16 releases the typewheel. Spring 39, through tape 14 and drum 13 generates the greater torque at the typewheel by about two to one and overcomes spring 17. The typewheel spins clockwise as the 8 or 10 units of tape withdrawn from retractor drum 37 is retracted. In the same time the movement of arms 61, 62 and 65 and their looper pulleys continues, further taking up tape 14, until the typewheel is drawn around the full 21 units from datum position. At this point the pull on the tape quite sharply stops because the retractor drum and looper pulleys reach their limits. Energy stored in the typewheel causes some overthrow.

The preferred typewheel is so light, for one having independent manifolding types, due to the construction described, that high speeds may be obtained with relatively weak springs, i. e., with low energy. The overthrow is opposed by spring 17 which has been increasing more in tension the farther and faster the tape and spring 39 have spun the typewheel. There is provided an incidental damping friction due to spring 26 pressing the typewheel body against fibre washer 71 on the face of boss 9. A stopping of the typewheel is thus obtained in which the stored energy is dissipated fully as quickly as is needed for high speed typing, yet without shock. The centering pin 16 next darts into the hole 15 at position 21—this accompanies and very slightly precedes the blow of the typing hammer—and the bell mouth of hole 15 with the pointed end of pin 16 enforces correct centering if the amplitude of the typewheel oscillation at that instant is only less than one type space. Letter number 21 is printed.

Having considered the operation of the selecting means when producing a large clockwise displacement of the typewheel (always viewed as in Fig. 1), let us consider a reverse displacement. The typewheel is now held by centering pin 16 at position 21. As will be seen from the timing diagram, power bar 66 is first quickly returned to the left. This permits the operated arms 61, 62 and 65 to follow to the left under the influence of springs 76, 77 and 80 respectively. (Springs 78 and 79 similarly restore arms 63 and 64 respectively, when operated.) As this occurs slack would be thrown into tape 14 if the corresponding looper levers and pulleys, 44 and 32, 43 and 31, 47 and 35 followed. But springs 81, 82 and 79 respectively retain the three operated looper levers in their existing or "long loop" positions and maintain snugness in tape 14. Springs 77 and 76 would act in the same way, when needed, to re-

tain respectively looper levers and pulleys 45 and 33, 46 and 34 in "long loop" position.

The typewheel is now held at position 21; the retractor drum 37 has taken up all it can of tape 14, being against its stop; the 21 units of tape length corresponding to typewheel position No. 21 are lightly held out by springs 81, 82 and 79 so that slack in tape 14 will not occur. Let us assume the combination of selectable arms 61 and 10 63 will next be engaged by bar 66 and moved to the right. These two, or the looper levers they operate, can take up only 1 plus 2=3 units of tape. This is a very small part of the 21 units of tape length now available before any can be pulled 15 from the retractor drum 37. Furthermore, before bar 66 has completed its power stroke and taken up even the three units (through arms 61 and 63) the centering pin releases the typewheel. This time, because there is a surplus rather than 20 a deficit of tape length and because retractor drum 37 has not been unwound at all, it is spring 17 that spins the typewheel, counterclockwise, until the tape tightens suddenly against the retractor drum 37 and its spring 39. Springs 81, 82 25 and 79 were first overcome and looper pulleys 32, 31 and 35 were pulled to their "short loop" positions. The stopping conditions for the typewheel at position 3 coming from position 21 are nearly as before, except that the overthrow or first half 30 cycle of oscillation meets spring 39 instead of spring 17.

The above broadly describes the two typical cases of selective typewheel positioning by the means of this invention: going to a higher numbered position and to a lower numbered one. It will be noted that in either case the typewheel spins directly from the letter or character last typed to the new one. It will also be noted that no motion of carriage frame 5 along rails 4, 4 can 40 have any effect on the perimeter of the path followed by tape 14. Hence, except for an infinitesimal pause to print, the carriage may be moving at any time.

The code receiving and storing means used and 45 the means to make these control the selective positioning of the typewheel requires explanation. As stated earlier, the embodiment shown is arranged to work on stop-start circuits. In Fig. 2, 83 is a driving shaft to which may be connected 50 through suitable gearing an electric motor with a flywheel and a governor, a synchronous motor or any adequate source of power of reasonably constant speed. The speed of shaft 83 depends on the printing speed desired, one revolution of 55 the shaft as usual being required per letter or other code symbol. 84 is any well-known one-revolution clutch operable by either mechanical or electrical means to clutch shaft 85 to shaft 83 during one revolution and then to cause shaft 85 to stop 60 until or unless clutch 84 is again or has been again operated. A well-known line relay chosen and adjusted to the line or channel used and to the speed desired and an electrical stop-start distributor or equivalent are assumed to be used 65 with the mechanism disclosed.

Fig. 6 shows at R in end elevation a strip of 5 code storing electromagnets. The detail of one of these is better shown in Figs. 8 and 9, because other parts partially cover the view of this element in Fig. 6. 86 is a brass or other non-magnetic angle support for a set of five magnets. It may extend from side wall to side wall of the case like plates 48 and 49 or be supported firmly otherwise. 87 is a magnetic pole piece attached 70 firmly to angle 86 as shown. 88 is a soft iron

core; 89, 89 are spool heads on the core and 90 a magnet coil between the spool heads. 91 is a hardened steel screw threaded into core 88 to hold it to pole piece 87. The core and the pole piece are of equal height. Lying flat and iron to iron on their end surfaces is shown armature 92 having a central tongue 93 protruding through a clearance hole 98 in brass angle 86.

Armature 92, on the slightly acute corners 97, pivots in a knife edge manner in the re-entrant 10 90° corner formed by end of pole piece 87 and side of angle 86. Tongue 93 is drawn outwards and upwards as shown by a light spring 94 adjustable by bending spring support lug 95. Angle 86 is tapped for adjustable armature back stop screw 15 96 with lock nut. Armature 92 carries brass spring holder 99, on a narrow lug on which is forced a close wound coil of fine spring wire 100. One end of the wire extends axially beyond the coil and then bends at right angles to form sloping 20 switch end 101 movable by armature 92 close to one surface of power bar 66. The shape and relation of this switch end to bars 61 to 65 and to certain interference members carried by power bar 66 appears clearly in Fig. 1.

Pivoted at 103 in channel shaped power bar 66 is a wire 102 bent into a wide U. The end of the pivot leg is seen at 103. The other end of U wire 102 crosses the channel bar 66 in two small slots 104, 104 and protrudes a small distance at 105. End 105 falls naturally to the bottom of slots 104. This it may only do if switch end 101 is below the foot of slot 104 as shown dotted at 106 in Fig. 1. This is the position of switch end 101 when armature 92 falls against back stop screw 96. The coil 90 of each of the five magnets R comprises two windings. There is a main operating winding for each magnet connected to a well-known receiving distributor to receive each the impulse of a different code period or time channel.

Thus if marking impulses come in all five code periods all five magnets R will be energized by their operating windings. If period 1 and 5 are marking and 2, 3, 4 spacing, then only magnets 1 and 5 will be so energized and the others not. A 45 small winding, opposingly connected to the operating winding, forms part of each coil 90. These five small de-energizing coils are connected in series and through interrupter 106 on shaft 85 to a 50 source of direct current, which may be the same as is used to energize the operating coils of magnets R. Interrupter 106 passes no current through the de-energizing coils until power bar 66 has carried ends 105 of U shaped interference members beyond the point of engaging arms 61—65. Slight notches 107 are provided in arms 61—65 to retain ends 105 once engaged.

The hardened steel screws 91 in the end of cores 88, once these magnets have been strongly energized in the operating direction, renders them 60 very retentive or sticky, and an attracted armature 92 will retain that position until the de-energizing windings are energized via interrupter 106. This wipes out the previous code and the magnets are in condition to receive and retain a new code. This new code will energize the magnets during the time that wires 105 on bar 66 are to the right of the points of arms 61—65. If a wire 105 was lifted by the corresponding switch 70 101 and engaged an arm, 64 for example, and carried it to the right in the motion of power bar 66, the magnet armature 92 and switch 101 after being knocked down via interrupter 106 may either have risen again or stayed down, depending 75

on the code received. If it stayed down, wire 105 will drop to the bottom of slot 104 as soon as bar 66 returns to the extreme left. If the armature and switch rose again, then wire 105, on the return stroke of bar 66 and arm 64, will negligibly depress switch 101 and will then be held up by the latter until bar 66 starts to the right and grips it in notch 107.

If, however, arm 64 was not moved on the last code, yet if switch 101 is now up due to a newly received code, then, as bar 66 returns to the left, wire 105 will ride under the sloping end of arm 64 and in so doing will depress switch 101 by a little less than twice the diameter of wire 105 until wire 105 passes the point of arm 64. Switch 101 is so flexibly connected, however, by spring coil 100 to armature 92 that this amount of movement will not cause the armature to fall.

The use of five code storing magnets and the whole described method of receiving and storing codes is not broadly new, and forms but a negligible part of this invention. The use of magnets made purposely of high residual magnetism with a de-energizing or knockdown impulse is a convenient and novel cheap device of this sort. Any man skilled in the art can adapt to the raising or lowering, according to a code, of wires 105, or of a set of switches equivalent in function to switches 101, one of several well-known purely mechanical means of receiving and storing codes. This would be particularly desirable when mechanical rather than electrical timers are in use to distinguish each code impulse from the next, such as are usually called mechanical distributors.

Fig. 11 shows the typewheel, of which the various numbered parts have been identified, in its relation to the matter being typed. The type 21 at position P is the one about to be printed. The last letter printed, T, is legible although the lowest part is not visible. It is convenient, to maintain legibility of the last letter while avoiding a ribbon shifting device, to present a narrow typewriter ribbon 127 vertically before the type in position P. Ribbon 127 comes from a supply spool (not shown) at the left of the machine to left main guide 130 (Fig. 3) carried on top of hammer guide lug 123. It makes a right angle bend around guide 130 toward the paper, also a 90° twist, and comes to top spool guide 128—which is supported on rod 129 from the other hammer guide lug 131, of frame 5—passing downward over this guide and between the type faces and paper platen 1.

It angles slightly away from the typewheel in this downward stretch, the more easily to clear the type faces, makes a right angle bend around lower spool guide 132 toward the back of the machine, also a 90° twist, coming to right main guide 133. Guides 132 and 133 are carried on rod 134 coming from carriage frame 5. The ribbon rounds right main guide 133 to extend either to another supply spool (not shown), at the right hand side of the machine, or else to run over a pulley and back to a supply spool at the left side of the machine. Arrangements for taking up and letting off typewriter ribbons and for reversing them are very many and well-known. One of them may be used here. The sole peculiarities are that the ribbon feeding movements of the supply spools in this machine are preferably to be caused by the carriage return only, rather than by carriage steps or spaces, that these movements preferably should not be an integral multiple of the letter spaces and that the ribbon should not be slack.

As the carriage, 5, spaces along rails 4, 4 during typing, with the ribbon supply spools stationary, the stationary ribbon will be drawn through the moving carriage, over the guides just described, presenting a fresh spot for each new letter. If, when the carriage returns, the ribbon is shifted thereby, but not a multiple of the letter space, fresh spots will again be presented for the whole next line, etc. This ribbon feed per line arrangement as described is a convenient one for this machine, but may be replaced by any well-known feeding arrangement. The vertical or nearly vertical position of the ribbon at the printing point is, however, to be preferred for visibility in cooperation with the non-central typing point and non-radial type relationship of this invention.

In this machine as shown the typewheel is displaced on all so-called "stunt" codes exactly as if they represented characters. This offers no objections and avoids the construction of a device to prevent the raising of the typing hammer and centering pin on the "stunt" codes. Such a device might be a latch on the rear end of type hammer 28 in place of cross pin 120, and a bail to lift it, operated by the falling of any one of the "stunt" code bars (to be described). The word space, for which any desired code may be chosen, say code 27, is merely a blank or typeless position in the typewheel. The position S in Fig. 11 may be the word space, though no fixed code and order of letters has been assumed for this machine, since its adaptability to cooperation with existing arrangements is paramount. The typing hammer 28 falls on position S, or on any other blank position, in the usual way. Its stroke is however checked by the horseshoe collar 122 striking the back shoulder of neck 124, so that without the thickness of a type 21 interposed before the paper hammer 28 makes no mark. The blow of the hammer is cushioned by spring 125, as described. Lacking a type to strike the compression of this spring is slightly greater, so that the impact on collar 122 is not sharp.

In this machine, as is usual, four codes are reserved for machine operations other than printing and spacing, usually called "stunts". Pursuant to the requirement of cooperating with present arrangements these codes can be any four. For purposes of illustration they have been chosen thus:

Code 28—Carriage return
Code 29—Line space
Code 30—Shift or "figures"
Code 31—Unshift or "letters"

The mechanisms for performing these "stunts" are controlled by four code bars. The code cuttings of the shift code bar 135 and of the unshift code bar 136 are best seen in Fig. 1. Those of the carriage return code bar 137 and of the line space code bar 138 are seen in Fig. 4. Obviously each of these bars could be cut for any desired code other than that shown.

These four code bars are pivoted at 139. They are raised by the tumblers 140, 140 (see Fig. 7), carried by power bar 66, as the latter comes to the left; they are held raised by flat top pin 141 cooperating with lugs 142—142 on all four code bars, until power bar 66 has made a portion of its power stroke. They then drop under the influence of springs 143—143. At this time the selectable arms 61 to 65 have each either been engaged with power bar 66 and moved from normal or will not be moved. These arms carry cross pins 144 that

prevent the code bars falling, when finding no notches, as the support of pin 141 is removed.

Unshift code bar 136 is so notched that it cannot fall unless all five of arms 61 to 65 have been moved to the right. The notches are of such length that they do not limit the further movement of pins 144, and are cut progressively deeper the farther they are from pivot 139. This condition that all arms 61 to 65 shall move before code bar 136 falls makes the code to drop the latter be 1 plus 2 plus 4 plus 8 plus 16=31, which is the code above arbitrarily assigned. Shift code bar 135 has one narrow notch 145 above the normal position of cross pin 144 of arm 61 instead of a wide notch above the moved position of that pin. It is otherwise notched like code bar 136. It thus requires for falling that arm 61 be not moved and that arms 62 to 65 be moved. This corresponds to code 0 plus 2 plus 4 plus 8 plus 16=30. From these examples the notching and condition of falling of code bars 137 and 138 will be self-evident.

Shift code bar 135 determines the swinging to the left of shift pulley 29, and hence the taking up of 31 units of length of tape 14. This causes position 32 of the typewheel, counting from datum position, to replace position 1, 33 to replace 2, etc. These are the upper case characters. As long as pulley 29 is at the left, these characters will be positioned, instead of the corresponding letters, before the typing hammer.

Lever 148, carrying pulley 29 on a stud projecting through plate 48, is pivoted at 147. This lever is slotted through, except at the two ends, as shown in Fig. 2. Cam rider 150, with roller 151, is pivoted in lever 148 at 149. Spring 152 causes it to follow cam 153. Rider 150 thus rocks on every cycle. The upper part of 150 is formed with an overhang or beak 154. Mounted on the side of lever 148 is a pin 156 supporting a short coil of spring wire 157 the end of which extends through the two walls of lever 148 in vertical slot 155. The end of code bar 135 lies close to lever 148 and is formed to a curve 158. When code bar 135 drops as described, its curved edge 158 tends to raise wire 157 into engagement in notch 159 in beak 154 of rider 150. This it cannot accomplish until roller 151 reaches the low of cam 153. Timing diagram Fig. 12 shows that this occurs quite late in the cycle.

As cam 153 raises roller 151, notch 159 grips interference wire 157 and rocks lever 148, with pulley 29, to the left. In the upper part of the slot of lever 148 lies latch roller 160. Latch 162, on fixed pivot 163, engages latch roller 160 beyond its shoulder 161 when cam 153 reaches its high, and retains pulley 29 in shifted or "figures" position. It will be seen from Fig. 12 that all but the very start of this cam action takes place in the succeeding cycle. The cam rise in the cycle initiated by the "shift" code (30 as elected) goes only far enough to grip interference wire 157. The code bar 135 is lifted, i. e., restored to normal at the end of the "shift" code cycle.

Delaying thus the extension of tape 14 by pulley 29 into the succeeding cycle makes it unnecessary to spin the typewheel more than half way in any cycle. Using code 30 for "shift" if the 31 units of rotation due to the movement of pulley 29 by cam 153 were superimposed on the 30 units due to looper pulleys 31, 33, 34, 35, the time allowed for typewheel rotation, as shown about $\frac{3}{5}$ of the cycle, would have to be greater, making the cycle longer in all cases. By only spinning the typewheel to position 30 and lock-

ing it there in the "shift" cycle, and letting the 31 units due to pulley 29 be delayed as described into the next cycle, even if that next cycle is on a high numbered code, (e. g., 26), the type-wheel will only have to move 31 plus 26 minus 30=27 units. Were the code chosen for "shift" a low number, such as 1, then cam 153 could be timed to complete the movement of pulley 29 within the "shift" cycle. Many existing systems, use the higher numbered codes for "stunts" so that it was desirable for complete adaptability to show the use of high numbered stunt codes.

There is no such problem of excessive type-wheel movement in the "unshift" cycle if a high numbered code is used. The 31 extra units taken up by pulley 29 may be released at the same time as the 31 units of the "unshift" code are taken up by the looper pulleys 31 to 35, thus bringing the typewheel to position 31 from whatever "upper case" position it had occupied. Code bar 136, therefore, when it falls, merely trips latch 162 from roller 160. This it does by striking pin 164 on latch 162 with its upper extension 165.

The carriage 5 is drawn to the left (Fig. 4 view) along rails 4, one step in every cycle, by tape 166, which wraps on drum 167. Drum 167 is made fast to ratchet 172 and is stepped by live pawl 168 on cam rider arm 169 and holding pawl 171. Cam 170 reciprocates arm 169. A gap 173 in the teeth of ratchet 172 is provided to prevent feeding the carriage too far and doing damage if an operator fails to send "carriage return" in time. Spiral spring driven drum 175 by tape 174, (which may be a continuation of tape 166), urges carriage 5 to the right as seen in Fig. 4, i. e., to the start of the printing line. Provision of a suitable dash pot to absorb the carriage energy is assembled. The carriage of this invention is inherently much lighter than of prior art page printers. The start of line position is given by the stop pin 176 on drum 167 striking stop 177. 178 is a cam plate on the same center as ratchet 172. By center passing spring 179 and center avoiding strap 180 it is normally held in the position shown where its lug 181 is against the stationary pin 182 on which holding pawl 171 pivots.

Cam plate 178 when turned counterclockwise raises pawls 168 and 171 out of engagement, letting ratchet 172 and drum 167 return to start of line position under the pull of spring drum 175. Cam plate 178 is moved to do this by live pawl 168 itself, when dog 183, fast to cam plate 178, is raised to engage pawl 168. Code bar 137, by bell crank arm 184, stud 189, and link 185, swings dog 186 to raise dog 183 by the pin 187. Live pawl 168 then catches and moves dog 183 and thereby turns cam plate 178 so as to disengage holding pawl 171. Live pawl 168 was not, itself, able to engage a tooth of ratchet 172 because it carried cam plate 178 forward beneath itself. Cam plate 178, once the line of action of center passing spring 179 is past the center, remains with its lug 188 against pin 182. This prevents pawl 168 from engaging a tooth of ratchet 172 should a new code come in before the carriage is fully returned. When drum 167 and ratchet 172 are brought to start of line position a pin 190 in ratchet 172 drives cam plate 178 to where center passing spring 179 again throws it to normal. This center passing spring arrangement is to provide for the case where the carriage return code might be sent after only one step of the carriage away from start of line.

Line space code bar 138 is connected by link 75

191, slotted at the top, to link 192 (Fig. 6). Spring 193 draws the latter up and to the right as shown. Link 192 thus normally presses pawl arm 194 back to stop 195. Cam 119 is fixed on shaft 115 as already described, and rocks slotted follower arm 197 about its center 198 on frame stud 199 once in every cycle, by means of roller 200. Spring 201 causes arm 197 to follow cam 119. When the notches in code bar 133 agree with the pattern of pins 144 set up by the selection, it falls and, by link 191, pulls down link 192. The hook end 202 of link 192 is in the slotted end of arm 197 so it engages tooth 203 in coming down. Pawl arm 194 is thereby swung and pawl 196 rotates ratchet 204 one tooth. This turns platen 1 one line space. Notched plate 205 and jockey roller 206 retain it in this position until the next line space.

In Fig. 16 is diagrammatically shown an alternative connection of tape 14, in which both ends wrap on the drum 13 of the typewheel. This requires doubling the stroke of the looper pulleys compared to the Fig. 1 arrangement. It also requires a substitute for the retractor drum 37 and spring 39, which may be a yielding connection of shift pulley 29 to the shift lever 148. The advantage of such an arrangement is the lesser accuracy required in the stroke of the looper pulleys and the balanced or pure torque applied to the typewheel.

In Fig. 13, 10A is the typewheel body mounted on stud 6A, 12 the rear flange with centering holes 15, 14 the tape and 13 the tape drum. Moulded into the type body is a thin steel fingered disc 11A carrying type 21 brazed or riveted on the fingers in the angular arrangement shown in Fig. 15. The fingers 22A are bent away from the paper as shown. A non-rotating type clamping guide 20A is pivoted at L on a suitable lug of carriage 5, and provided with a strong spring 26A and a stop 27A.

As best seen in Fig. 14, when the flat end of typing hammer 28A strikes a finger 22A, the latter is gripped between the upper end of type clamping guide 20A and the lower part of the end of the hammer 28A, and is thus advanced against the paper substantially in a parallel manner, the type 21 being itself supported by the upper part of hammer 28A. An advantage of this form of construction is the still lower mass of the revolving typewheel, due to the type clamping guide—equivalent in type guiding function with disc 20 of Fig. 3—not being part of the rotating mass, due to the type stems or bodies 22 not being used, and due to disc 11A being lighter than flange 11.

It will be noted that on the timing diagram, Fig. 12, one suitable relation to the cycle of an ordinary start-stop five-unit code has been indicated. It is there assumed that the beginning of the "stop" impulse—after the code impulses have been stored in magnets R, or in any well-known equivalent storage—is used to start the one-revolution clutch. This is not necessary. The mechanical cycle may be initiated at any point in the code cycle—i. e., at any phase of the receiving distributor—subject to the fact that the code should be fully stored before the power bar grips the selectable arms 61 to 65. The relative length of this diagram of the code times to the mechanical cycle times is to be disregarded.

Many other variations and practical embodiments of the above principles will occur to those skilled in the art, and may be practiced without

departing from the spirit of my invention as set forth in the appended claims.

What I claim is:

1. In an automatic typing mechanism, a type member, a flexible tensile means to position said type member, a centering means more accurately to position said type member, a plurality of selected means cumulatively determining a longitudinal displacement of a portion of said tensile means, a printing presser, and means for operating said printing presser when said centering means has positioned said type member. 5 10

2. In an automatic typing mechanism, a paper support, a carrier of types adapted to be displaced selectively to present a desired type in printing relation to paper on said support, means to move said carrier in one sense, a flexible non-extensible tensile means to move said carrier in an opposed sense, a plurality of loopers each adapted to take up a predetermined loop of said tensile means to displace said carrier to predetermined positions, a plurality of looper movers, means selectively to render said looper movers operative under control of a selecting device and means to center and lock said carrier in any of several positions. 20 25

3. In an automatic typing mechanism, a type carrier having a plurality of type members, a plurality of selectively movable members severally and jointly displacing said type carrier through an equalizing connection for selectively positioning a type member for printing thereof, said connection including a flexible non-extensible filament and a pulley, a carrier locking means for locking said type carrier in position for printing of a selected type member thereof, and a type presser for pressing a selected type member for effecting printing thereof. 30 35

4. In an automatic typing mechanism, a traveling carriage including a type carrier displaceable thereon, a plurality of selectively movable members not on said carriage adapted severally and jointly to displace said carrier on said carriage different amounts through an equalizer, said equalizer including a non-extensible filament with both ends attached on said carriage and a plurality of pulleys not on said carriage. 40 45

5. In an automatic typing mechanism, a carrier for a number of type faces, a typing bar to strike said type faces against a paper, a belt to move said carrier to present different type faces before said bar, a plurality of loopers capable of additively pulling said belt predetermined amounts, selective means to render said loopers operative in accordance with code designations, and a centering locking means for said carrier effective before said typing bar strikes and during a portion of the operating time of said loopers. 50 55

6. In a printing telegraph machine, a pivoted type carrier having a plurality of type members, a striker for striking said type members individually to effect printing thereof, means for operating said striker, a driving means for said type carrier, a drum on said type carrier, a flexible tensile member wrapped on said drum to pull said type carrier around against said driving means, movable loopers in contact with said tensile member each extending a predetermined bight therein when moved, a centering means for accurately positioning said type carrier, and means for operating said type member before said striker is operated. 60 65 70

7. In a printing telegraph, a set of type faces, a pivoted carrier for said set, a spring to rotate said carrier in one direction, a flexible tensile 75

- member to rotate it in the other direction to position it, several loopers movable to extend each a predetermined bight in said tensile member, an elastic storage to permit said loopers to move in advance of the corresponding rotation of said carrier, code recording means, means selectively to move said loopers in accordance with said recording means, a registering means for accurately positioning said pivoted carrier and for holding it during part of the moving of said loopers, and a printing bar to make an impression of that one of said set of type faces positioned before it through said tensile member and said registering means.
18. 8. In a code controlled typing mechanism, a carriage movable back and forth in a path, a printing bar thereon, mounted also on said carriage a carrier of type faces selectively presentable before said bar, power means causing said bar to print individual type faces so presented, several pulleys mounted on means other than said carriage, a loop of flexible tensile material operatively connected at one end to said carrier and drawn over said pulleys by motion of said carriage, instrumentalities comprising certain of said pulleys and means other than the motion of the carriage for varying the perimeter of said loop, and means for additively operating said instrumentalities.
30. 9. In a page printer, a traveling carriage, a movable type carrier on said carriage, a loop of tape, five code loopers to enlarge said loop of tape by therein extending smaller loops taking up respectively one, two, four, eight and sixteen units of length of said loop of tape, said loop of tape connecting to said carrier to position it and passing over said loopers, means selectively to operate any one or ones of said loopers, and centering means for said carrier.
40. 10. In a page printer, a carriage, a movable type carrier on said carriage, a loop of tape, a set of code loopers not on said carriage to control the perimeter of said loop of tape by therein controlling smaller loops, said loop of tape connecting to said carrier and passing over said loopers, means selectively to operate any one or ones of said loopers, a case shift looper over which said loop of tape also passes, and means to operate said case shift looper dependent on the operation of a certain combination of said code loopers.
50. 11. In a printing telegraph machine, the combination of a type carrier having a plurality of type members, a type presser for pressing said type members to effect printing thereof, selective positioning means for selectively positioning said type carrier comprising a tape, a storage spring, and several tape take-up means selectively operable, and registering means for supplementing said selective positioning means for positioning said type carrier more accurately than said selective positioning means.
65. 12. In a page printing telegraph, a traveling carriage, a movable type member thereon, a spring to move said type member one way, a tape connected at one end to pull said type member against said spring and at the other end so connected to said carriage that the first end travels with said carriage, and means not on said carriage to take up and let out said tape to move said type member either way.
70. 13. In a printing telegraph, the method of selectively moving a type member from any of a range of selectable positions to stop cushionedly at another that comprises: locking the type member at one of the positions while applying to it a force urging it in one direction, then applying to it a stronger force tending to urge it in the other direction while selectively limiting the range of the stronger force, and then releasing the type member.
14. In a printing telegraph, a rotatable type wheel and a device to displace selectively and to stop the same with slight shock comprising opposed unequal springs for acting upon said type wheel, means to lock and unlock said type wheel and means including a flexible tensile member and selectively movable pulleys selectively to limit while said typewheel is locked the range of action of the stronger of said springs.
15. In a printing telegraph, a weaker spring, a stronger spring, a limit stop for the latter, a type member a flexible tensile connection between said type member and said stronger spring, means selectively to vary the effective length of said tensile connection, means including said springs to bring said type member to rest where said weaker spring is stopped by said tensile connection to said stronger spring, and registering means for said type member.
16. In an automatic typing mechanism, a weaker spring, a stronger spring, a flexible tensile connection to the latter, an action limit for said stronger spring, a type member urged by said weaker spring and stopped by said flexible tensile connection, and means to take up or let out selected lengths of said tensile connection.
17. A printing telegraph machine for printing upon a page of paper and comprising in combination, a traveling carriage including a disc shaped rotatable carrier having a plurality of holes therein, a plurality of peripherally arranged individually hinged types on said carrier each attached at an angle to its carrier radius and comprising lower and upper "case" characters in two separate groups sequentially, a typing bar on said carriage, means for causing the typing bar to strike said types at a position below and to the left of the top center of said disc-shaped carrier, a yielding guide against which said types may be gripped one at a time by said bar and together with which they may by said bar be driven to printing position on a radius longer than their individual hinges, a type registering spur for engaging one of the holes in said carrier to register it before said bar drives one of said types to printing position and remaining in such engagement for a dwell thereafter, a cushion stop for said typing bar to retract at once said bar from the extreme printing position, a home spring urging said rotatable carrier toward a home position, a drum on said rotatable carrier, a tape fastened to and wrapping on said drum in the sense to oppose its tensile pull to said home spring and extending over rollers to another fastening on said traveling carriage, five loopers for engaging with said tape and capable respectively of extending bights therein of one, two, four, eight, and sixteen units of length for causing one, two, four, eight, and sixteen units of rotation of said carrier from its home position by the unwrapping of said tape from said drum, power means for selectively energizing said loopers, means for operating said power means at least partially during the dwell of said spur when in engagement with one of the holes in said carrier, a stop, resilient retractile means having its retractile stroke limited by said stop and yielding to let out lengths of said tape for permitting operation of said power means during the mentioned dwell and for storing energy from said power means

- for rotating said carrier against said home spring after the dwell, a shift looper for taking up more than twenty-six units of said tape causing said carrier to maintain positions where one group of 5 said types comprising characters of one "case" is beyond said typing bar counting toward the home position, one shift code bar, a source of power, means for operating said shift code bar for engaging said shift looper with said source 10 of power when one combination of said five loopers is energized by said power means, a second shift code bar, and means for operating said second shift code bar for restoring said shift looper when another combination of said five loopers is 15 energized by said power means.
18. In a page printing telegraph, a traveling carriage, a movable type member thereon, selective positioning means for said type member comprising a loop of tape operatively connected 20 at one end with said type member and connected with said carriage at the other and comprising five loopers selectively operable to vary the perimeter of said loop of tape, a carriage moving belt to restore to starting position said traveling carriage, a spring take-up for one end of said belt to cause it to restore said carriage to starting position, means including a ratchet to advance said carriage in letter spacing steps, a holding pawl for said ratchet, a cam to disengage said 25 holding pawl from said ratchet and a carriage return code bar operating when one chosen combination is operated of said five loopers to cause to move said cam to disengage said holding pawl.
19. In a page printing telegraph, a traveling carriage, a movable type member thereon, selective positioning means for said type member comprising a loop of tape operatively connected 30
- 35 at one end with said type member and connected with said carriage at the other and comprising five loopers selectively operable to vary the perimeter of said loop of tape, a paper platen, a ratchet to rotate it by steps, a power-driven cam, a line space code bar operating when a chosen combination is operated of said five loopers to connect said power-driven cam to said ratchet.
20. In a printing telegraph machine, a movable type carrier having a plurality of type members 10 and having a number of selectable stopping positions, actuating means for urging the type carrier in one direction for moving said type carrier to the selectable stopping positions, biasing means for constantly urging the type carrier in an opposite direction with a force weaker than that of the actuating means for cushioning the stopping of the type carrier when it is moved to a selected stopping position by the actuating means.
21. In a printing telegraph machine, a movable type carrier having a plurality of type members, 20 a type presser for pressing said type members to effect printing thereof, actuating means for moving the type carrier into position for printing by said type presser and a selected type member, 25 said actuating means including a spring, a flexible tensile connection between the type carrier and the spring for enabling the spring to move the type carrier, control means for selectively varying the effective length of said connection 30 for varying the amount of movement of the type wheel, an instrumentality for limiting the action of said spring, and checking means for checking the momentum of the type carrier after it has been moved by said actuating means. 35

ARTHUR H. ADAMS.
